(57) **CLAIM**

We claim, the ornamental design for a flat headed mop, as shown and described.

DESCRIPTION

FIG. 1 is a front, top perspective view of our new design for a flat headed mop;

FIG. 2 is a rear, top perspective view thereof;
FIG. 3 is an enlarged front, top perspective view taken from FIG. 1;

FIG. 4 is an enlarged front, bottom perspective view thereof;

FIG. 5 is a rear elevation view thereof;

FIG. 6 is a front elevation view thereof;

FIG. 7 is a right side elevation view thereof;

FIG. 8 is a left side elevation view thereof;

FIG. 9 is a top plan view thereof; and,

FIG. 10 is a bottom plan view thereof.

The broken lines in the drawings depict portions of the flat headed mop that form no part of the claimed design.
